KNOB ROSE

Van Day Truex, New York, N. Y., assignor to The Yale & Towne Manufacturing Company, Stamford, Conn., a corporation of Connecticut

Application March 23, 1956, Serial No. 40,750

Term of patent 7 years

(Cl. D50—6)

Fig. 1.

Fig. 2.

Fig. 3.

Fig. 1 is a front elevation of a knob rose embodying my new design.

Fig. 2 is a top plan view of the knob rose.

Fig. 3 is a section on the line 3—3 of Fig. 1.

I claim:

The ornamental design for a knob rose, substantially as shown.
